UNITED STATES PATENT OFFICE.

JAMES G. VETETO, OF AMITY, ARKANSAS.

GUN.

1,267,293.

Specification of Letters Patent. Patented May 21, 1918.

Application filed October 15, 1917. Serial No. 196,877.

To all whom it may concern:

Be it known that I, JAMES G. VETETO, a citizen of the United States, residing at Amity, in the county of Clark and State of Arkansas, have invented certain new and useful Improvements in Guns, of which the following is a specification.

This invention relates to fire arms and more particularly to fire arms of the type 10 wherein an electric current is employed to fire the cartridges.

The primary object of the invention is to provide a magazine gun adapted for firing electric cartridges; and to arrange within 15 the gun suitable electricity generating and switching means whereby an electric current may be passed through the cartridges to explode the same.

Another object of the invention resides in 20 the peculiar combination and arrangement of parts whereby the gun is rendered compact and efficient and the switching and other elements thereof so disposed as to operate reliably at all times.

25 Other objects of the invention as well as the construction and use thereof will be more readily understood from the following description and accompanying drawings in which drawings.

30 Figure 1 is a side elevation of a magazine-pistol embodying my invention, and

Fig. 2 is a view similar to Fig. 1 partly broken away to show the inside mechanism.

In the drawings, I have shown a magazine 35 pistol embodying my improved features of construction and which comprises a hollow stock or handle 1, a barrel 2 and a frame 3. As more clearly shown in Fig. 1 the stock or handle is made hollow and has arranged 40 therein a pair of spaced vertical walls 4 which define a space or magazine chamber 5 to receive suitable electric cartridges 6. This magazine 5 is provided with a cartridge carrier 7 beneath which is arranged a compression spring 8 and this plate or cartridge carrier serves to support the cartridges in the usual manner and to feed the same toward the upper end of the magazine chamber. To give access to the magazine chamber 45 a suitable opening is formed on one side of the stock 1 and is normally closed by means of a suitable swinging door 9.

Formed in the frame 3 and arranged beneath the barrel 2 is a chamber 10 which may 55 be of any suitable configuration and is adapted to house a suitable electric battery

or cell 11. The forward end of this chamber is closed by the hinged door 12 which is provided with a spring clasp 13 adapted to be engaged over a suitable projection 14, 60 formed on the lower wall of the chamber. The rear end of this battery chamber is separated from the hollow stock 1 by means of a partition wall 15, and arranged to slide through the central opening 16 of this partition is the longer arm of an L-shaped contact 17. The shorter arm of this contact is arranged within the rear end of the battery chamber as shown and has its free end enlarged as at 18 and positioned in alignment 65 with one pole 19 of the battery, with which pole it is adapted at times to be engaged. On the longer arm of the contact is arranged a binding post 20 to which is connected one end of a suitable electric conductor 21, the 70 opposite end of this conductor being connected to a stationary contact 22 positioned on the inner end of the barrel adjacent the bore thereof. A lug 23 depends from the longer arm of the contact, adjacent the free 75 end thereof and has fastened thereto one end of a coiled spring 24 the opposite end of which spring is secured to one of the vertical walls 4 of the magazine chamber. This spring pulls the contact rearwardly and thus 80 normally holds the same away from the battery and out of engagement with the pole 19 thereof.

Engaging the rear edge of the lug 23 is the upper end 25 of a trigger 26 which is 85 pivotally secured in the frame in the usual manner. In order to enable the circuit to be completed when the L-shaped contact 17 is in engagement with the pole 19 of the battery the opposite pole 27 of this battery 90 is electrically connected with the partition wall 15 as by means of a conductor 28, thus providing a return for the current.

In the operation of the gun, one of the cartridges 6 is arranged in the rear end of 100 the barrel in the usual manner and it will be noted that the cap or primer of the cartridges is in engagement with the contact 22. When the trigger is pulled back the upper end thereof being in engagement with the 105 lug 23 will force the movable contact 17 forward against the tension of the spring 24, thus bringing the shorter arm of this contact into engagement with the pole 19 of the battery, thereby completing the circuit. 110 The current passes from the pole 19 through the contact 17, and wire 21 to the contact 22

from whence it passes through the primer or cap of the cartridges exploding the same in the usual manner. The current returns to the opposite pole of the battery through the metal of the gun and the wire 28.

No special construction of electric cartridge has been shown in connection with this invention as the invention resides in the construction of the gun alone and any suitable cartridges of this type may be used in connection therewith.

Furthermore it is to be understood that the form shown and described constitutes only a preferred embodiment of the invention and therefore I do not limit myself to the exact details of construction and arrangement shown, but may resort to such changes as may be desired providing of course that the same come within the scope of the claims and do not depart from the spirit of the invention.

I claim:—

1. In an electric fire arm, the combination with the stock, barrel and trigger of a gun, of an electric battery having one pole thereof electrically connected with the metal of the gun, a sliding contact movable into and out of engagement with the opposite pole of the battery and adapted to be operated by the trigger, a stationary contact secured to the barrel, and an electrical connection between said stationary and sliding contacts.

2. An electric fire arm, including in combination with the stock, barrel and trigger of a gun, a chamber arranged beneath the barrel, a battery in said chamber, a sliding contact movable into and out of engagement with one pole of said battery and adapted to be operated by said trigger, a stationary contact secured to said barrel and an electrical connection between said stationary and sliding contacts.

3. An electric fire arm, comprising in combination with the stock, barrel and trigger of a gun, a chamber arranged beneath said barrel, a battery positioned in said chamber and having one pole electrically connected therewith, a sliding contact movable into and out of engagement with the opposite pole of the battery and adapted to be operated by said trigger, a spring normally holding said contact away from the battery, a stationary contact connected to the barrel and an electrical connection between said stationary and sliding contacts.

4. In an electric fire arm, the combination with the stock, barrel and trigger of a gun of a chamber arranged beneath the barrel, a battery positioned in said chamber and having one of its poles electrically connected

therewith, an L-shaped sliding contact adapted to be operated by the trigger and having the shorter arm thereof movable into and out of engagement with the opposite pole of the battery, a stationary contact secured to the barrel and an electrical connection between said stationary and sliding contacts, and means to normally hold the sliding contact away from the battery.

5. In an electric fire arm the combination 70
with the stock, barrel and trigger of a gun,
of a chamber arranged beneath the barrel, a
battery positioned in said chamber and hav-
ing one of its poles electrically connected
therewith, an L-shaped contact mounted for 75
sliding movement and having the shorter
arm thereof adapted to be engaged and dis-
engaged with the opposite pole of the bat-
tery, a lug depending from the longer arm
of the contact and adapted to be engaged
by the trigger, means connected with said
lug to normally hold the contact away from
the battery, a stationary contact secured to
the barrel, and an electrical connection be-
tween the stationary and sliding contacts. 80
85

6. In an electric fire arm, the combination with the hollow stock, barrel and trigger of a gun, of a pair of vertical spaced walls arranged within the stock and forming a magazine for the reception of the cartridges, a chamber arranged beneath the barrel, a battery positioned in said chamber and having one of its poles electrically connected therewith, a partition wall separating the chamber from the stock, a movable contact adapted to be operated by the trigger and arranged to slide through said partition for engagement with the opposite pole of the battery, a stationary contact secured to the inner end of the barrel, and an electrical connection between said stationary and movable contacts. 90

7. A pistol including the combination with a stock, a barrel, and a pivotally mounted trigger, of an insulated contact mounted in the barrel, a battery having one of its poles electrically connected with the said barrel, a sliding contact electrically connected with said stationary contact and engaging said trigger, said sliding contact adapted to be moved into and out of engagement with the other pole of the battery by the actuation of said trigger. 105 110

In testimony whereof I affix my signature
in presence of two witnesses. 115
